PERMANENT WAVING DEVICE

George Decker, Cincinnati, Ohio, assignor of one-half to Phil D. Spaeth, Cincinnati, Ohio, and one-half to Adolph Kietz, Bellevue, Wash.

Application January 15, 1936, Serial No. 59,273

20 Claims. (Cl. 132—36)

This invention relates to a moisture supplying means for use in permanent waving and has for objects to provide for supplying moisture in vapor form adjacent a wound curl of hair, to supply such moisture from a suitable container held adjacent such curl by a portion of the regular permanent waving equipment, to supply such moisture from a receptacle containing absorbent material and adapted to emit moisture upon being heated and otherwise to retain such moisture irrespective of the action of gravity.

A further object is to combine the moisture containing receptacle with the heater whereby its use will occasion but little change in operating procedure.

With the foregoing and other objects in view, the invention consists in the novel features and combinations and arrangements of parts herein-after described and illustrated in the accompanying drawing wherein Fig. 1 is a sectional view taken through a heater embodying the invention; Fig. 2 is a section on the line 2—2 of Fig. 1; Fig. 3 is a central vertical section taken at right angles to the plane of Fig. 1 and Fig. 4 is a fragmentary detail view of the moisture container showing the cartridge partially removed from its receptacle.

In the drawing, the numeral 10 indicates the heating elements of a two-part sectional heater adapted to heat a curl wound on a conventional curler rod R. The heating elements are surrounded by shells 11, preferably of metal, to which are connected as by welding, soldering or otherwise, metallic attaching elements 12 having inturned lugs 13. Attached to the main body of the elements 12 as by rivets 14 are handles 15 preferably composed of insulating material such as hard rubber, phenol condensate or the like. Passing through the handles are conductors 16 and 17 leading from insulated conductors 18 and 19 each to one side of a resistance heating element embedded in the insulation and with such insulation making up the heaters 10. The other terminals of the resistance elements of the heaters 10 may be connected together by a conductor 20 having an exterior insulated portion 21.

Pivoted to the elements 13 are ears 22 carried by a receptacle 23. The ears 22 may be secured to the receptacle 23 by spot welding, soldering or in any suitable manner, it being desirable that the contact be metal to metal and that the ears 22 engage tightly against the elements 13 whereby to provide a low resistance heat path from the heaters 10 to the receptacles 23. Springs 24 are provided in holding relation to the pintles 25

which pivotally connect the elements 13 and 22 for the purpose of constantly urging the heaters 10 toward each other whereby to grip a wound curl of hair in a manner which will be well understood by those skilled in the art of permanent waving.

The receptacle 23 is provided with outlet means 26 and is adapted to receive a cartridge 27 containing absorbent means 28, such as cotton and provided with a vapor outlet means 29. It will be obvious from the drawing that one end of the container made up of the receptacle 23 and the cartridge 27 is positioned between the edges of the heating elements 10 whereby its lower surface forms substantially a continuation of the curve 15 of each of the heating elements and is thereby adapted to engage against a wound curl gripped between such heating elements or the covering thereof. The positioning of the outlet means 26 closely adjacent the curl or its covering makes 20 for efficient application of moisture vaporized within the cartridge 27 to the curl itself and reduces the amount of such moisture which is emitted into the atmosphere. The cartridge 27 may be held frictionally within the receptacle 23 25 or special means may be provided for holding it in position. Any suitable means (not shown) may be provided for introducing the absorbent material 28 into the cartridge 27 either initially or for renewal and such opening may be provided 30 with a closure if desired. With the construction shown, the thickness of the container may be such that in position of use, the adjacent portions of the heater will come very close to the walls thereof so as to vaporize the moisture in the adjacent end of the cartridge 27 and this, together with the heat conducting path of the elements 13 and 22, will be sufficient to vaporize the moisture carried by the material 28 and cause the same to be supplied to the curl or the absorbent 35 covering which is usually provided for supplying the waving solution thereto as the initial moisture is driven off by the heaters 10. In this way, I provide a safeguard against undue drying out of the curl and the possibility of overheating.

This device is in a measure automatic, the cartridge 27 being considerably elongated so that moisture close to the curl is subjected to a temperature approximating that at the surface of the curl itself with the result that vaporization 50 occurs more rapidly at the lower end of the cartridge 27 and vapor is supplied to the curl or its absorbent covering in direct proportion, both to the temperature and the dryness thereof. The fact that the cartridge 27 is elongated, per-

mits the use of a considerable reserve supply of moisture which will not be used in normal operation but which will automatically become available to prevent overheating or burning.

5 The type of heating in connection with which the invention is important may be distinguished from the type wherein an aqueous heating fluid is conducted to the curl from an outside source by the designation "dry-type".

10 While I have shown and described the preferred embodiment of my invention, I wish it understood that the same is susceptible of being embodied in substantially dissimilar devices and I therefore do not wish to be limited to the details 15 shown but only in accordance with the appended claims.

Having thus described my invention, what I claim is:

1. In combination with a sectional, electrical 20 resistance heating means adapted to be brought into heating relation to a wound curl, a moisture containing means attached thereto and carried thereby and adapted to supply moisture to said curl.

25 2. In a permanent waving device, means upon which a curl may be wound, an elongated moisture absorbent means, means for supporting said moisture absorbent means with one end adjacent a curl wound on said first means and extending substantially radially outwardly therefrom, and means for heating said curl.

3. In combination with a sectional electrical 35 resistance heater for permanent waving, a moisture container carried thereby and having a vapor outlet in one face only thereof, said container being connected to said heater in a manner to present said vapor outlet adjacent a curl being heated by said sectional heater.

4. In combination with a sectional heater for 40 permanent waving, a moisture container carried thereby and having a vapor outlet, said container being connected to said heater in a manner to present said vapor outlet adjacent a curl being heated by said sectional heater, said container being pivotally connected to one section of said heater.

5. In combination with a sectional heater for 45 permanent waving, a moisture container carried thereby and having a vapor outlet, said container being connected to said heater in a manner to present said vapor outlet adjacent a curl being heated by said sectional heater, said container having the wall which contains said vapor outlet lying substantially on a continuation of a 55 curve corresponding to a curl engaging surface of said heater.

6. In combination with a sectional heater for 60 permanent waving, a moisture container carried thereby and having a vapor outlet, said container being connected to said heater in a manner to present said vapor outlet adjacent a curl being heated by said sectional heater, said container being pivotally connected to two sections of said heater and positioned to engage a curl therebetween or its covering.

7. In a permanent waving device, a container 65 having an outlet, moisture absorbent material in said container and means for holding said container in position that said outlet is adjacent a curl and heating the moisture therein, said container comprising a receptacle and a removable cartridge containing an absorbent material.

8. In combination with a heating means adapted to be brought into heating relation to 70 a wound curl, a moisture containing means car-

ried thereby and adapted to supply moisture to said curl, said moisture containing means comprising a receptacle and a removable cartridge containing an absorbent material and having vapor outlet means, said receptacle also having 5 vapor outlet means, said outlet means being positioned to emit moisture adjacent said curl.

9. In combination with a heating means adapted to be brought into heating relation to a wound curl, a moisture containing means carried thereby and adapted to supply moisture to said curl, said moisture containing means comprising a receptacle and a removable cartridge containing an absorbent material and having vapor outlet means, said receptacle also having 10 vapor outlet means, said outlet means being positioned to emit moisture adjacent said curl and said moisture containing means being connected to said heating means by metal whereby to form a low resistance path for conduction thereto of 15 heat from said heater.

10. In combination with a heating means adapted to be brought into heating relation to a wound curl, a moisture containing means carried thereby and adapted to supply moisture to 20 said curl and said moisture containing means being connected to said heating means by metal whereby to form a low resistance path for conduction thereto of heat from said heater.

11. In combination, a sectional heater having 25 curved heating portions adapted to embrace a wound curl, a container having a perforate portion positioned to engage the curl or its covering between the edges of said curved heating portions, handles connected to said heating portions 30 and pivoted to said container and spring means urging said curved portions toward each other.

12. In combination, a sectional heater having 35 curved heating portions adapted to embrace a wound curl, a container having a perforate portion positioned to engage the curl or its covering between the edges of said curved heating portions, handles connected to said heating portions 40 and pivoted to said container and spring means urging said curved portions toward each other, said container comprising a receptacle and 45 a removable cartridge containing absorbent material.

13. In combination, a sectional heater having 50 curved heating portions adapted to embrace a wound curl, a container having a perforate portion positioned to engage the curl or its covering between the edges of said curved heating portions, handles connected to said heating portions 55 and pivoted to said container and spring means interposed between each of said handles and said receptacle for urging said curved portions toward each other.

14. In combination with a heating means adapted to be brought into heating relation to a wound curl, an elongated moisture containing means having a vapor outlet at one end and being otherwise closed, and means for supporting the same with said vapor outlet adjacent said curl, said moisture containing means being attached 60 to and carried by said heating means and comprising a container having absorbent material therein.

15. In a permanent waving device, moisture absorbent means, a container therefor, and electrical resistance means for heating a curl and vaporizing the moisture in said absorbent means, said container being attached to and carried by 70 said electrical resistance means.

16. The combination with a sectional heater 75

for permanent waving, a moisture container, and heat conducting means mechanically and thermally connecting said container with said heater whereby rapid vaporization of the moisture in 5 said container is effected when the heater is operated.

17. In a permanent waving device, the combination with a heater of the clamp-on type including a pair of pivotally mounted heating 10 elements adapted to be clamped over a wound curl, a moisture dispensing container mechanically and thermally connected with said heating elements and disposed radially outside of the wound curl for supplying vapor in proportion 15 to the temperature and dryness of the curl.

18. In a permanent waving device, an elongated moisture container, a pair of heating elements including a pair of pivotally mounted clamping jaws adapted to be clamped around a wound 20 curl, said moisture container being heated by said heating elements and having one or more vapor outlets disposed immediately adjacent said heating elements and radially outwardly of the wound

curl whereby vapor will be supplied to the curl in proportion to the temperature and dryness thereof.

19. In a permanent waving device, a moisture dispensing container having a dispensing outlet 5 and containing moisture absorbent material, a pair of heating elements secured to said container and adapted to be secured over a wound curl, said container being so positioned as to discharge moisture immediately adjacent said heating elements but exteriorly of the wound curl whereby vapor will be supplied to the curl in proportion 10 to the temperature and dryness thereof.

20. In a permanent waving device, a pair of heating elements adapted to be secured around 15 a wound curl, moisture dispensing means supported by said heating elements and positioned so as to deliver moisture to a point immediately adjacent said heating elements but exteriorly of said wound curl whereby vapor will be supplied 20 to the curl from the outside thereof in proportion to the temperature and dryness of the curl.

GEORGE DECKER.
